UNITED STATES PATENT OFFICE.

GEORGE WESTINGHOUSE, OF PITTSBURG, PENNSYLVANIA.

FURNACE.

SPECIFICATION forming part of Letters Patent No. 708,107, dated September 2, 1902.

Application filed March 25, 1901. Serial No. 52,684. (No model.)

To all whom it may concern:

Be it known that I, GEORGE WESTINGHOUSE, a citizen of the United States, and a resident of Pittsburgh, in the county of Allegheny and State of Pennsylvania, have invented certain new and useful Improvements in Furnaces, of which the following is a specification.

My invention relates to improvements in the class of apparatus employed for smelting ores and other materials, and particularly to that form of apparatus commonly referred to as "cupola-furnaces."

The object of the invention is to provide a furnace in which the heat which is usually wasted shall be conserved and usefully applied in the smelting operation and at the same time the furnace itself made more convenient and economical as to its construction and operation. In the ordinary practice it has been customary to provide such furnaces with walls of refractory material or with water-cooled jackets, the heat radiated by the refractory material or absorbed by the water being for the most part wasted. It has heretofore been suggested also that it is practicable to use air instead of water for cooling blast-furnace jackets and for heating the blast. On this point James Douglas, in a paper on the Metallurgy of Copper, read in England before the Society for the Encouragement of Arts, Manufactures, and Commerce on May 5, 1895, said: "A real improvement would be devising an air-jacketed furnace which would not buckle and in which the blast could be raised to a much higher degree than could be done by simply air-jacketing the crucible." It has also been proposed to cool the furnace by means of an air-jacket in which streams of air are to be directed against the wall of the furnace. So far as I am aware, however, no means have heretofore been devised for securing such a circulation of air with such an intimate contact thereof with sufficient radiating-surface on the part of the inner walls of the furnace to secure sufficient effective cooling of those walls to prevent them from becoming overheated and at the same time to impart the requisite heat to the air, nor has there, so far as I am aware, been produced prior to my invention an air-jacket for such a furnace having such mechanical strength

and construction as to prevent injurious buckling under the influence of the varying temperatures to which it is subjected. It is 55 important to observe also that the mere directing of air against a relatively smooth surface of a furnace-wall is not sufficient to abstract the heat therefrom with sufficient rapidity, for such a wall does not possess sufficient radiating-surface to communicate to the particles of air the necessary heat in order to maintain the wall at a safe temperature.

I have devised an air-jacket of such form and internal structure as to have great 65 strength and the necessary characteristics to prevent injurious buckling and at the same time insure that practically all of the air as it passes therethrough shall impinge against heat-radiating surfaces in intimate relation 70 to the wall of the furnace, particularly that portion adjacent to the smelting zone. For this purpose the jacket is provided with numerous closely-arranged heat-radiating ribs in intimate relation to or mechanically united 75 with the wall of the furnace-jacket, and means are provided for directing the air continuously against these ribs and through the spaces about them.

My invention further contemplates certain 80 special constructions of the furnace in which an air-jacket incloses the crucible and in which those portions which are liable to be injured or destroyed by continuous use are made replaceable.

The invention will be more particularly described in connection with the accompanying drawings, in which—

Figure 1 is an elevation, partly in section, of a complete furnace. Fig. 2 is an enlarged 90 view of a portion of the furnace-wall; Fig. 3, a perspective view of a portion of the wall; Fig. 4, a transverse section of a portion of the furnace, and Fig. 5 a section of a modified form of jacket. Figs. 6 and 7 illustrate a 95 method of employing the invention in connection with certain other apparatus.

Referring to the figures, 1 represents the lining of the crucible of the furnace, composed of any suitable refractory material. 100 This lining is contained within and embraced by a wall 2, constructed with suitable air-passages into which air is forced through an opening 3. The portion of the furnace above

the crucible is formed or built of hollow boxes 4, constituting both a wall and an air-jacket, and of air-heating passages 14, which communicate with the air-space 3^a, inclosing the 5 crucible.

The general object of the invention is to cause the air used for blast purposes to abstract the jacket-heat resulting from smelting operations in such an efficient manner as 10 to keep the interior wall of the furnace within reasonable and safe temperature limits and at the same time utilize the heat so abstracted for producing more efficient smelting operations in the furnace. This is accomplished by causing the air to pass downward around the ribbed furnace-wall, in such 15 intimate contact therewith as to abstract a relatively large amount of heat therefrom and to be then passed through suitable openings into the smelting zone. The air, therefore, when it is admitted through the passage 3 passes through the space beneath and around the crucible and contained within the boxes 6. The air then passes through the 20 air-passages 14 to the top of the furnace. The upper ends of these air-passages communicate with the upper ends of the upper tier of boxes 4. The air-passages 14 may be conveniently formed in castings which constitute 25 the outer walls of the air-jacket, the inner walls consisting of the boxes 4, which are removably attached to the plates 15, constituting the outer wall. The plates 15 are formed into rectangular boxes by means of 30 corner-posts 15^a, to which they are bolted.

The construction of the boxes 4 is more clearly illustrated in Fig. 3. By referring to this figure it will be seen that there are two series of vertical ribs 16 and 18. The ribs 16 40 may be cast integral with the supporting-wall 14^a of the box, or they may be of soft iron placed in the mold in such manner as to become integral with the walls 14^a when the box is cast. The vertical ribs 18 are also cast integral with the wall 14^a, and intervening inclined baffle-plates 17 are cast between the ribs 18, and these also serve to strengthen the 45 whole structure. The baffle-plates 17 are inclined toward the inner surface of the boxes, so that air descending from the top of the 50 furnace-wall will be directed against that wall and the surfaces of the heat-radiating ribs 16 and 18. In practice it is convenient to construct the furnace with two or more such boxes 4, to be fastened to each outer plate 15, one box being placed above the other. They 55 are fastened to the outer plate by bolts 30 or in any other convenient manner for permitting their removal and replacement. The upper box is bolted against an angle iron or 60 plate 15^b, which forms the top portion of the furnace. It is important that the space constituting the air-jacket should be thus provided with very great heat-radiating surface, 65 for I have found in practice that unless there be a large amount of metal in actual mechanical contact with the inner wall of the furnace

the heat cannot be carried away with sufficient rapidity, and this metal should be so organized and arranged as to present very 70 great heat-radiating surface, and the air-blast should be circulated in such manner as to bring it into close contact therewith. The arrangement described brings the ribs into such relation, they being integral with the 75 wall 14^a. For the purpose of delivering the heated air to the furnace the lower ends of the lower jackets 4 are open through the inner wall 14^a, so that the air may pass directly therefrom into the furnace. The passages 14 80 are shown as being rectangular longitudinal boxes cast integral with the outer wall 15, and at the upper end they are closed by the plates 15^b, which surround the upper portion of the furnace. The upper ends of the upper 85 boxes are closed by the same plates, and the upper ends of the ribs 18 are cut away, as shown in Fig. 3, to permit the ready entrance and distribution of air therethrough. In the drawings I have shown dampers or regulating-valves 21 in the passages 14, and for the purpose of affording access to the bottom of the furnace openings 20 are provided at the lower ends of the outer plates 15, these openings being closed normally by weighted lids 90 22. A convenient construction is to enlarge the distance between the bottom of the plates 15 and the lower ends of the boxes 4, as shown, for instance, by the dotted lines 20^a, Fig. 2. These weighted lids serve also as a 100 convenient means for stopping the blast operations by permitting the air to escape from the bottom of the furnace after passing through the air-jacket.

Suitable spouts 24 and 36 may be provided 105 for drawing off the contents of the crucible, when desired, in a well-known manner.

In Fig. 5 a modification is illustrated in which the boxes 4 are built up of outer cast-metal sections 31 and intermediate rolled-metal sections 32. These latter may be rolled with ribs 18^a and fitted together, as clearly shown in the drawings. The inner ends are dovetailed together and present an inner wall 14^a. The entire set of plates are held together 115 by bolts 33.

In Figs. 6 and 7 an organization is shown wherein a furnace of the character described is employed in connection with an exterior air-heating device 41. This consists of a tubular heater through which the hot products of combustion from the smelting-furnace may be passed by a pipe 42. These products pass downward around the tubes of the heater, thence through a dust-box 44 of any well-known convenient construction to a stack 45. A by-pass 46, provided with a damper 47, may be employed for permitting more or less of the hot products of combustion to pass direct to the dust-box in order to regulate the preliminary heating of the air. A suitable air-pump 48 forces air through the heater and into pipes 49, leading to the air-jacket of the furnace. In this manner more or less of the

heat which might otherwise be carried away by the products of combustion may be imparted to the air before it is delivered to the furnace-jackets. In these figures the pipes 5 conveying the air to the furnace are shown as delivering the air directly to the passage 14; but it will be understood that they may deliver air beneath the crucible to the passage 3, as before.

10 The furnace is also shown as being provided with a hood 50, which may be closed at the top by a damper 51 when desired.

I claim as my invention—

1. In a smelting-furnace, an air-jacket consisting of wall-plates having vertical ribs and transverse baffle-plates integral with the inner surface of the plates, the baffle-plates extending across the spaces between adjacent ribs, substantially as described.

2. A smelting-furnace having its outer walls composed of vertical plates having air-passages, an air-inlet and an air-outlet leading to and from said passages, and its inner wall composed of plates having integral heat-radiating ribs, and means for securing the same to the outer wall.

3. A smelting-furnace consisting of a crucible and vertical air-jacketed walls and air inlets and outlets leading to and from the air-jacket, said walls consisting of hollow independently-removable compartments, and heat-radiating ribs integral with the inner walls thereof.

4. In a smelting-furnace, an inclosing wall 35 consisting of wall-plates of iron having heat-radiating ribs integral with one side thereof, and an outer wall to which the wall-plates are independently removably attached.

5. In a smelting-furnace, an air-jacketed 40 wall and air inlets and outlets leading to and from the air-jacket, said wall consisting of an outer supporting structure, and independently-removable sectional wall-plates having heat-radiating ribs integral therewith, substantially as described.

6. A removable section of wall for a furnace, consisting of a wall-plate having vertical and transverse heat-radiating ribs, the transverse ribs being inclined with reference 50 to the wall.

7. A furnace-wall consisting of a series of independently-removable heat-radiating sections, each section comprising a wall-plate having one surface presented to the reduction-chamber of the furnace and having its opposite surface constructed with heat-radiating ribs, and means for detachably securing the wall-plates in the furnace. 55

8. The combination with the wall-plate 4, of the vertical ribs 16 and 18 projecting from 60 one surface of the wall-plate, and the interposed baffle-plates inclined with reference to the surface of the wall-plate.

9. In a smelting-furnace, the combination of the outer walls, the vertical flues therein, 65 the inner vertical heat-radiating compartment with which said flues communicate at their upper ends, and the twyers with which said compartment communicates.

10. In a smelting-furnace, the combination 70 of the outer walls, the vertical flues therein, the inner vertical heat-radiating compartment with which said flues communicate at their upper ends, the twyers with which said compartment communicates, and the regulating-dampers in said flues. 75

11. The combination of the outer walls, constituting the shell of a furnace, the vertical flues therein, the openings at their lower ends, 80 the air-heating chamber beneath the crucible, the twyers, connections between the heating-chamber and the twyers and connections from the flues to the twyers.

12. The combination with the crucible of a furnace, of the inclosing wall, the vertical 85 flues carried thereby, an air-jacket beneath the crucible communicating with the vertical flues, an air-jacket within the wall of the furnace, connections from the upper ends of the flues with said air-jacket, and openings 90 from the lower end of the jacket into the furnace.

Signed at New York, in the county of New York and State of New York, this 19th day of March, A. D. 1901.

GEO. WESTINGHOUSE.
